UNITED STATES PATENT OFFICE.

DANIEL J. DAVIS, OF CHICAGO, ILLINOIS.

CENTRIFUGAL SEPARATOR FOR LIQUIDS.

SPECIFICATION forming part of Letters Patent No. 521,104, dated June 5, 1894.

Application filed November 11, 1893. Serial No. 490,653. (No model.)

To all whom it may concern:

Be it known that I, DANIEL J. DAVIS, of Chicago, Cook county, Illinois, have invented certain new and useful Improvements in Centrifugal Separators for Liquids, of which I do declare the following to be a full, clear, and exact description, sufficient to enable others skilled in the art to make and use the same.

The details of structure usual to one type 10 of the invention will appear from the description following and the improvements be thereafter more distinctly pointed out by claims at the conclusion thereof.

In the accompanying drawings forming a 15 part of the specification like parts are denoted by like designation throughout.

Figure 1 is a view of the centrifugal separator and its tier-pans in vertical section. Fig. 2 is a cross-section view at line 2—2 of 20 Fig. 1 with the reservoir discharge pipe removed.

The inclosing safety-cage A is provided as usual with box-bearing *a* for the neck of driving-axle B which latter conveniently carries 25 the base *c* of the revolving drum or bowl C. The main wall of the drum is here shown in cylindrical form with the base *c* threaded thereto and at its opposite end the drum terminates in a neck-piece D shouldered as appears and threaded to the vertical part of the 30 wall. At a suitable point in the neck below its throat an outlet is provided which as here shown consists of a hollow screw-plug *d* threaded to a hole in the neck; said plug having 35 a counter-sunk mouth and being rounded at its outer end to afford better clearance for the liquid discharge. By adjusting the plug *d* in or out it presents more or less obstruction and thereby regulates the out-flow. 40 Within the neck of the bowl and interspaced therefrom so as to afford a free passage or channel substantially around the whole circuit of the vessel is a separating dome E which conveniently conforms in shape to the 45 taper of the neck and shoulder of the vessel and is snugly inclosed by the throat of said neck beyond the vent hole *d*. The dome and neck are here shown threaded together at the throat with stop-flanges *e* between said parts. 50 The flanges serve to position the dome and neck in interspaced relation so as to leave a

slight and practically continuous inlet *f* where the edge of the dome comes next to the wall of the bowl. Such an inlet enables the skim-milk to be drawn away equally and evenly at 55 all points of the circuit. Disturbing cross-currents which ensue when leading tubes extend at one or more points into the skim-milk zone are quite eliminated. The separated skim-milk flows freely into the interspaced 60 channel without annoying influx or spurts of cream. The latter being exposed to no local induction keeps its place and preserves the integrity of its zone unimpaired. On rising to the outlet *d* the skim-milk escapes from 65 the bowl; the neck and dome affording a common chamber between them into which the whole of the skim-milk is drawn and from which it discharges. The snug joint between dome and neck beyond the outlet *d* closes the 70 chamber and compels the skim-milk to escape at the outlet.

The relation of the dome E in the bowl-neck enables the cream to rise clear and away after its separation until it finally clears the inset ledge *g* in the crown of the dome and enters the chamber *h* at the dome cap. The ledge *g* preferably has a notch or slit at one point, the radial depth of which is controlled by an adjusting screw *i* projected through the 80 dome wall. A discharge port *k* leads from chamber *h* and affords a vent for the cream into its receiving tray.

By making the dome E detachable from the bowl these parts are easily separated and become 85 fully accessible not only for washing but for free exposure throughout to sunlight and air. What is even more important, the structural relation is such as to enable the dome to be remounted again with entire accuracy even by the ordinary operator at the dairy.

In general practice, when bent tubes are used which lead the skim-milk from the vessel interior to discharge ports in the bowl-neck, the tubes are set at the factory and soldered in fixed position. By such expedient the bowl can thereafter be nicely balanced, the tubes be securely held against chance displacement under the enormous centrifugal 95 force prevailing while the soldered joint prevents the leak escape of cream around the 100

skim-milk port. Unless the tubes are thus fastened and accurately retained, the bowl becomes unbalanced which at high speeds exposes the attendants to great dangers and 5 completely destroys the precision of separation. The free exposure of the tubes to sunlight is never attained while the cleansing of the tortuous passages by the aid of special brushes is troublesome and oftentimes inefficient. The same objections apply, if attempt 10 be made as heretofore proposed, to use an interspaced dome soldered permanently to the bowl-neck or else cast in one piece therewith. To balance the drum with its parts in running 15 position is a bit of factory expert work of the utmost nicety. Once effected, the slightest deviation thereafter, becomes a source of untold mischief through the intensive action of centrifugal force. For which reason, the interspaced dome equally with the bent tubes 20 has been permanently set in place and could not be thoroughly cleansed nor be left to the purifying effect of the sun.

The present improvement enables the separating dome on removal to be restored again 25 quickly to position with entire exactitude. The stops interposed between the dome and the vessel-wall determine the interspace limit and maintain the dome at even poise. In 30 revolution, the tendency of the dome to "creep" upward is checked by the stops so that proper interspace for delivery of the skim-milk is insured. The relation of the dome joint at the throat of the drum-neck keeps the 35 bowl practically tight and no leak can there occur such as would otherwise diminish the regular discharge of the cream at its port in keeping with a given volume of skim-milk escaping at the outlet appropriate thereto.

40 By threading the dome joint, the turning of the drum tightens the dome to position and so far aids in holding the parts snugly together, keeps the machine balanced and operates to more certainly prevent leakage.

45 The circular pans or trays *l*, *m*, to receive the separated skim-milk and cream on discharge from the vessel are mounted as usual in tiers *i. e.*, above each other, about the bowl-neck and are sustained upon the safety jacket 50 *A*. The bottoms of the trays are inclined for drainage into the tubes *n*, *o*, while their tops by being inclined also, serve as baffles to arrest the flying skim-milk and cream as these are projected radially through the holes *d*, *k*.

55 The liquids fall in thin streams or sheets onto the tray bottoms and heretofore have been exposed to the influx of counter air currents which in the case of the cream especially has aerified it and rendered it "foamy."

60 The invention designs to correct this defect and to such end provides the vessel-neck with an overhang lip *p* projected into the cream tray slightly above the opening *q* which exists between the trays and the neck. A lesser lip *r* 65 may be projected in like fashion at the opening *s* between the neck and the bottom of the lower tray. The lid of the upper tray is shown to be

open at *t* for free admission of air. When the vessel revolves the overhang lip *p* being farther from the center exerts a certain force upon the surrounding air superior to that exerted by the adjacent parts of the neck and dome. Thereupon the tendency is to induce an air current toward the rim of the lip both from above and below. Air is drawn in at the 75 openings *t*, *q*, and along with the cream passes in same direction out of the tray at the tube *o*. The air no longer flows counter to the cream so that the latter becomes much less "foamy" in consequence. The inflow of air at the top opening *t* suffices to clear the lid of the upper tray from adherent cream while the inflow at opening *q* into said tray prevents portions of the cream from escaping into the lower tray which heretofore was 85 apt to occur when the set of the air current was in opposite direction, *i. e.*, from the cream into the milk pan through opening *q*. In-like fashion the lesser lip *r* insures clearance for the skim-milk to prevent its leak escape into 90 the dead-air space existing beneath between the bowl and the jacket. A trap *u* in the skim-milk spout checks ingress of air at that point and enables the ledge *p* to perform its function more certainly in directing the air 95 out at the cream spout *o*.

The reservoir *F* is mounted in usual fashion above the machine and has its discharge pipe *F'* opening into the tapering feed-tube *v*. Said tube extends through a bearing in 100 the cap of the separating dome *E* being positioned thereby and at its opposite end is sustained by a spider *w* set within a recess at the bowl bottom. The tube thus passes 105 through the neck and body of the vessel from end to end and delivers its supply into the sunken seat for spider *w* from which it overflows into the main part of the bowl. Radial wings *x* secured to a ring *y* are retained in 110 place within the vessel and act, as well known, to compel the revolution of the liquid contents in conjunction with the retaining drum.

The improvements have been described as for use in a dairy centrifugal but they are of equal advantage for the separation of any 115 other two liquids of different specific gravity. It is also obvious that the details of structure can be varied according to the skill of the mechanic without essential departure from the invention.

Having thus described the invention, what I claim as new, and desire to secure by Letters Patent, is—

1. In centrifugal separators for liquids, the combination with the drum having an elongated neck with an outlet therein, of the removable separating dome inclosed liquid-tight but detachably by said neck beyond the outlet thereof and interspaced from the drum-wall by a suitable stop whereby a free channel is established from the drum interior to the outlet at the neck, substantially as described.

2. In centrifugal separators for liquids, the

- combination with the drum having an elongated neck with an outlet therein, of the removable separating dome detachably threaded to said neck beyond the outlet and provided with a stop-flange to interspace it from the wall whereby a free channel is established from the drum interior to the outlet at the neck, substantially as described.
3. In centrifugal separators for liquids, the combination with the drum having an elongated neck with an outlet therein, of the removable separating dome detachably threaded to said neck beyond the outlet and provided with a stop-flange to interspace it from the wall whereby a free channel is established from the drum interior to the outlet at the

neck; said dome having an inset overflow ledge and a discharge port beyond the same and beyond the joint of the dome with the drum-neck, substantially as described. 20

4. In centrifugal separators, the combination with the surrounding tier-pans having air-inlet at top and usual discharge tubes, the lower of which is furnished with a trap or seal, of the drum-neck interspaced from said pans, and provided with an overhang lip located within the upper pan, substantially as described. 25
